UNITED STATES PATENT OFFICE.

SAMUEL K. WHITE, OF MYSTIC, CONNECTICUT.

DESIGN FOR A CUTTER-FRAME.

SPECIFICATION forming part of Design No. 31,751, dated October 31, 1899.

Application filed October 7, 1899. Serial No. 732,967. Term of patent 14 years.

To all whom it may concern:

Be it known that I, SAMUEL K. WHITE, of 5
Mystic, county of New London, and State of
Connecticut, have invented and produced a
new and original Design for Cutter-Frames,
of which the following is a specification, ref-
erence being had to the accompanying draw-
ings, forming part thereof.

In the drawings, Figure 1 is a perspective 10
view of a cutter-frame, showing my new de-
sign; and Fig. 2 is a perspective view looking
from the other side of the frame.

The leading feature of the design resides 15
in a cutter-frame having a general wedge-
shaped appearance. As shown in the draw-
ings, the sides A of the frame are substan-
tially triangular in outline, giving the frame
the general appearance of a wedge. There

is a rectangular opening B in the frame, the
upper side of which is formed by the cross- 20
piece C, which extends across from one side
to the other, and the lower side of which is
formed by the table D, which extends be-
tween the sides and also projects in front of
and back of said sides. 25

The design provides a cutter-frame which
presents a characteristic and distinguishing
appearance to the eye.

What I claim is—

The design for a cutter-frame substantially 30
as shown and described.

SAMUEL K. WHITE.
